(57) CLAIM

The ornamental design for a cap with septa, as shown and described.

DESCRIPTION

FIG. 1 is a top perspective view of a cap with septa, showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is an exploded top perspective view thereof;

FIG. 8 is an exploded bottom perspective view thereof; and, FIG. 9 is a top perspective view thereof, showing the cap with septa in a position of use with an exemplary vial.

The broken lines represent environmental subject matter of an exemplary vial as well as parts of the article, none of which form part of the claim.

1 Claim, 6 Drawing Sheets

Related U.S. Application Data

division of application No. 29/587,056, filed on Dec. 9, 2016, now Pat. No. Des. 858,281, which is a continuation of application No. PCT/US2015/063590, filed on Dec. 3, 2015.
